UNITED STATES PATENT OFFICE.

WILLIAM VAUGHAN ARTHUR, OF OAKLAND, CALIFORNIA.

DESIGN FOR A CHIN-REST FOR VIOLINS.

SPECIFICATION forming part of Design No. 17,111, dated February 15, 1887.

Application filed January 27, 1886. Serial No. 189,971. Term of patent 14 years.

To all whom it may concern:

Be it known that I, WILLIAM VAUGHAN ARTHUR, of Oakland, in the county of Alameda and State of California, have invented 5 and produced a new and original Design for a Chin-Rest for Violins, of which the following is a full, clear, and exact description.

The leading feature of my design consists in the configuration of the upper surface of the 10 chin-rest, which presents a concave depression extending obliquely across said upper surface, the concave figure of such depression being in direction of the length of the rest.

Reference is to be had to the accompanying 15 drawings, forming part of this specification, in which—

Figure 1 represents a view in perspective of a violin chin-rest having my new design. Fig. 2 is a plan view of the same.

20 A indicates the upper plate or portion of the chin-rest, the marginal configuration of which is of approximately-oval shape in direction of its length, presenting opposite rounded ends b b.

25 The leading feature of the design consists in a concave depression, c, in the upper surface of the portion A, said depression extending obliquely across said surface, and its concave being in direction of the length thereof. Such 30 concave depression c joins the upper surfaces of the end parts of the plate or portion A of

the chin-rest by gentle and easy convex configurations d d, thus giving an ornamental wave-like appearance to the top surface of the chin-rest.

The lower or stand part of the chin-rest is as here represented, and, when viewed from its side, of shoe-sole-like form, with a heel-like part, f, and, combined with the portion A, gives to the whole chin-rest a shoe-like appearance.

I claim—

1. In a design for a chin-rest for violins, as shown and described, the upper portion of the rest, ornamented with a concave depression extending across its upper surface on a line oblique to the longitudinal axis of the rest, and imparting a wave-like appearance to said upper surface, substantially as set forth. 45

2. The design for a chin-rest for violins 50 herein shown and described, the same consisting of the upper portion, A, of approximately-oval marginal configuration, with a concave depression, c, extending across its upper surface, and a lower portion resembling a shoe-sole with attached heel f, the whole giving to the chin-rest the appearance of a shoe, as herein set forth. 55

WILLIAM VAUGHAN ARTHUR.
